UNITED STATES PATENT OFFICE.

THOMAS SANDERS, OF KINGMAN, INDIANA.

TROLLEY-WHEEL MOUNT.

Application filed July 5, 1922. Serial No. 573,055.

To all whom it may concern:

Be it known that I, THOMAS SANDERS, a citizen of the United States, residing at Kingman, in the county of Fountain and State of Indiana, have invented a new and useful Improvement in Trolley-Wheel Mounts, of which the following is a specification.

My invention relates to that class of trolley-wheel mounts wherein a substantial mount is provided whereby a trolley-wheel is supported in bearings and upon the extreme end of a trolley-pole and with particular reference to the trolley-wheel mount described in Letters Patent No. 1,142,846, issued to this applicant under date of June 15, 1915, entitled "Trolley-wheel mounts."

And the objects of my invention are; first, to provide a suitable bearing and support for a trolley-wheel upon the extreme end of a trolley-pole; second, to provide such a device which by reason of its peculiar structure and attachments, permits an automatic adjustment in the position of the trolley-wheel while passing a curve in the trolley-wire, for the purpose of avoiding the danger of the trolley-wheel "jumping" the wire; and third, to provide such a device which will be substantial, slightly, safe from dis- placement and of economical construction.

These objects I attain by means of the device illustrated in the accompanying drawings in which:—

Figure 1, is a side elevation of the device.

Figure 2, is a view of the front edge of the device.

Figure 3, is a vertical sectional view of the device cut through the axis of the trolley-wheel.

Similar letters and numerals of reference refer to similar parts throughout the several views.

The numeral 2 indicates a trolley-wheel of the usual sheave-wheel type, provided with a hollow hub 3, which is rotatably mounted upon a shaft 4.

The shaft 4 is perforated to form an oil- vent 5, which extends from the center of one end to near the middle of the shaft and then curves outwardly to the surface of the shaft, and serves to feed oil to the bearing surface of the shaft, upon which the trolley-wheel revolves.

The letter A indicates a trolley-wheel mount which consists of a trolley-head 6 and a head-stock 7.

The trolley-head 6 consists of a U-shaped, or fork-like member, composed of a solid metallic base 8, and two parallel, upwardly projecting bearing-arms 9. The bearing- arms 9 are, each, provided with outwardly projecting and bevelled, hub-like journals 10, which are perforated centrally, to receive and support the ends for the shaft 4. Cotter-pins 11 transfix said journals 10, and the shaft 4, thereby holding said shaft stationary.

The base 8 is squared and proportioned to fit loosely upon the top of the head-stock 7, and is perforated vertically and centrally to receive the head-post 12. The base is thickened to form a substantial bearing for the head-post 12, and is perforated to form an oil-vent 15, whereby lubricant is fed to the bearing and head-post. The upper end of the head-post 12, is perforated to receive a cotter-pin 14, and a washer 15, takes up play between said cotter-pin 14 and the base 8.

Oblong slots 16 are cast in the sides of the bearing-arms 9; and strong brass springs 17, which are attached to the outer surface of the bearing-arms 6, by screws 18, pass through said slots 16 and upward upon the inner faces of the bearing-arms; and said springs 17 are perforated near the top to permit the passage therethrough, of the shaft 4 of the trolley-wheel.

When so mounted, the springs 17 serve as friction washers between the ends of the trolley-wheel hub 3 and the inner faces of the corresponding bearing-arms, and at the same time serve to hold the trolley-wheel firmly in normal position.

Recessed shoulders 19 are cut into the extreme lower edges of the two sides of the trolley-head for the purpose hereinafter set forth.

The head-stock 7 consists of substantial metallic body, enlarged and squared at the top and tapering downward to a ferrule-like shank 20; the lower end of said shank is hollow and adapted to receive the extreme end of a trolley-pole 21 upon which the head-stock is mounted, and fixed by a bolt 22. A ring-like projection 23, projects from one side of the shank 20, for the purpose of attaching a control-rope thereto.

The upper face of said head-stock 7, is squared and adapted to hold thereon the squared base of the trolley-head 6, and a head-post 12, projects upwardly from the

- center of the upper face of head-stock, and passes through the perforation in the center of the base of the trolley-head. The said head-post is perforated horizontally near its upper end and carries therein a cotter-pin 14, which confines thereunder, a washer 15, which rests upon the base, and takes up all lost play between the trolley-head and head-stock.
- 10 Strong flanges 24, project upwardly, from each edge of the two sides of the head-stock, and lap over upon the corresponding sides of the trolley-head opposite to the recessed shoulders 19, and are adapted to engage and 15 stop the base of the trolley-head when the same is turned to either side, and thus prevent the trolley-head from revolving too far, when the trolley-wheel is following a curved wire.
- 20 The advantages claimed for my improvement consist, first, in the substantial structure and ease of assembling and dismounting the various members, whereby the removal of the worn or broken trolley-wheel 25 and the substitution of new parts may be quickly and easily accomplished; second, by reason of the peculiar union of the trolley-head and head-stock and the space provided between the recessed shoulders 19 of 30 the trolley-head and the flanges 24 of the head-stock, a free revolving movement of the trolley-wheel is provided whereby the trolley-wheel is made free to follow a curving trolley-wire around corners and curves, 35 without any strain or wear upon the wheel or members of the mount; and third, the substantial and light structure of the mount renders the device economical, of long life, and attains a maximum of safety from 40 placement and incidental accidents.
- What I claim as new and useful, and desire to protect by Letters Patent, is:
1. The combination of a rotatable trolley-head and trolley-wheel axle or shaft with a head-stock adapted to movably support said trolley-head, a head-post integral with said head-stock, and adapted to confine said trolley-head in movable connection with said head-stock, upwardly projecting flanges 50 upon the upper edges of the sides of said head-stock, adapted to lap over the sides of said trolley-head and to engage and hold said trolley-head from excess movement, recessed shoulders cut into the lower edges of 55 the sides of said trolley-head and opposite to the two corresponding flanges of the head stock adapted to provide space for limited
- revolution of said trolley-head; a pair of oppositely disposed springs attached to said trolley-head and adapted to bear upon opposite sides of the trolley-wheel, all substantially as described and shown and for the purposes set forth. 60
2. In a trolley-wheel mount the combination of a rotatable trolley-head, said trolley-head consisting of a base and two bearing-arms, journal bearings in said bearing-arms adapted to support the shaft, a trolley-wheel, a trolley-wheel shaft, mounted in said journal bearings and adapted to support a trolley-wheel, means of fixing said trolley-wheel shaft in said journal bearings, with a head-stock adapted to support said trolley-head upon the upper face, a head-post integral with and upwardly projecting from said head-stock adapted to confine said trolley-head in rotatable connection with the head-stock, a pair of flanges projecting upwardly from said head-stock and upon opposite sides of said trolley-head and being adapted 70 to prevent excess movement of the trolley-head, recessed shoulders in the lower edges of the trolley-head, adapted to permit necessary movement of said trolley-wheel between said flanges of the head-stock, a pair 75 of oppositely positioned springs attached to the sides of said trolley-head and adapted to bear upon either side of the trolley-wheel, all substantially as described and shown and for the purposes set forth. 80
3. In a trolley-wheel mount, consisting of a rotatable trolley-head and a fixed head-stock, in movable connection with each other, means of movably attaching said members together, a pair of opposing springs attached to said trolley-head and adapted to bear against the sides of the trolley-wheel and to serve as friction washers between said trolley-wheel and corresponding portions of said trolley-head, a shaft journaled 90 in said trolley-head and adapted to support said trolley-wheel, a pair of flanges upon the top of said head-stock adapted to regulate the rotation of said trolley-head, a hollow shank integral with said head-stock 95 adapted to fit upon the end of a trolley-pole, means of attaching said head-stock to said trolley-pole, all substantially as shown and described. 100
